Fig. 3.

UNITED STATES PATENT OFFICE.

JOSEPH F. SMART, OF NEW BRITAIN, CONNECTICUT, ASSIGNOR TO LANDERS, FRARY & CLARK, OF NEW BRITAIN, CONNECTICUT, A CORPORATION OF CONNECTICUT.

THERMAL CIRCUIT BREAKER.

Application filed July 31, 1923. Serial No. 654,890.

This invention relates to means for cutting off the circuit from an electrically heated utensil as it approaches a dangerous degree of heat, the aim of the invention being to provide a device of this sort having features of novelty and advantage.

More particularly, the object of the invention is to provide a circuit breaker of this sort which is very sensitive in operation in that it will break the circuit with surety when the temperature of the utensil, with which it is associated, rises to within very small limits of the temperature at which the device is adjusted; which may be reset a very short time after the device has been automatically operated; which may be adjusted with nicety to operate at any predetermined temperature above which it is dangerous to heat the utensil; which is compact and economical in construction and which is housed within the utensil so it does not detract from the appearance of the utensil and so that it cannot be injured nor readily tampered with; and which may be manipulated or set in a ready manner without removing any parts or disassembling the utensil.

Other objects of the invention will be part obvious and in part pointed out more particularly hereinafter.

30 In the accompanying drawings:

Figure 1 is a top plan view of an electrically heated utensil, for instance a sad iron, in which is embodied one form of my invention, the cover of the iron being removed for purposes of clearness, and the parts of my circuit breaker being illustrated in latched or "on" position;

Fig. 2 is a side view of the sad iron looking in the direction of the arrow 2 of Figure 1 and with the casing of the iron in central longitudinal section;

Fig. 3 is a view similar to Figure 1 but with the parts of the circuit breaker shown in unlatched or "off" position;

45 Fig. 4 is an enlarged sectional view, taken substantially on line 4-4 of Fig. 3; and

Fig. 5 is a fragmentary view, in top plan, of a portion of the handle of the sad iron with the setting lever of the circuit breaker positioned therebeneath.

In the drawings, I have shown my device applied to a sad iron, but it is to be understood that my invention is applicable for use generally on electrically heated utensils, the present disclosure being by way of illustra-

tion only and, therefore, it is not to be taken as restrictive of my conception.

Referring to the drawings in detail, *a* denotes the sole plate of the iron; *b*, a solid metal top plate; and *c*, an electrical heating element of any suitable construction positioned between the sole plate and the top plate and insulated therefrom. *e* is a sheet metal cover or casing which encloses the top plate, the heating unit, and the thermostatic device or cut-out of the present invention; and *h* is a handle suitably held in place on the casing as by means of screws or bolts *f*.

The thermostatic device of the present invention includes a circuit closer having, in the present instance, a pivoted plate 10 resiliently carrying a circuit closing element 11 adapted to engage, and thereby close the circuit between, the contact members 12 and 12^a interposed in one of the leads of the heating unit *c*; a thermostat 9 arranged to hold the circuit closer in circuit closing position until the utensil reaches a predetermined heat, resulting in the thermostat being flexed and disengaged from the circuit closer whereupon the latter will be thrown into "off" position breaking the circuit through the electrical heating unit; and the setting device or lever 13 positioned on the outside of the casing and adapted to be manually operated to place the circuit closer in "on" position after the iron has cooled sufficiently to permit the thermostat to hold the circuit closer in this position.

The thermostat 9 comprises a pair of bi-metal bars 14 and 15 each secured at one end to a U-shaped sheet metal plate 16 pivoted for rotary movement on the top plate by means of a screw 17. Fixed to one end of one of the bi-metal bars, in the present instance the bar 14, is a sheet metal U-shaped plate 18 in which is journaled an anti-friction roller 19 adapted to engage and hold the pivoted plate 10 in circuit closing position, as hereinafter described more in detail. The thermostat 9 is normally urged in a direction to engage the roller 18 with the circuit closer, by means of a spring 20 positioned about the screw 17. The other bi-metal bar 15 is arranged to flex in a direction opposite to that in which the bi-metal bar 14 bends when the temperature of the utensil rises, and is adapted to engage, at its free end, against a suitable stop, 110

- which stop is, by preference, adjustable so as to regulate the temperature at which the circuit breaker will operate. In the present instance, this stop is in the form of a screw 21 adjustably carried by the top plate. It is, of course, understood that each of the bimetal bars is composed of two strips of metal having different co-efficients of expansion and welded or otherwise secured together. In the present illustrative disclosure, the strips of metal having a lesser co-efficient of expansion are positioned on the outside of those strips which have a great co-efficient of expansion.
- 15 The latch plate 10 is pivotally mounted on the top plate by a screw 23 and is normally urged by a spring 24 in a counter-clockwise direction, referring to Fig. 1, that is in a direction in which the circuit closing element 11 is moved away from the contacts 12, 12^a. The latch plate 10 is provided with a depending tongue 26 to which is secured, by means of a spring 27, the circuit closing element or contact blade 11. The contact blade is, of course, suitably insulated from the latch plate. The latch plate is further provided with a shoulder or stop 30 against which the anti-friction roller 19 is adapted to engage and thereby hold the circuit closer in latched or "on" position.
- 20 Fixed to the top plate *b*, as by means of one of the nuts *d*, is a supporting bracket 34 on the up-turned portion of which the contacts 12 and 12^a are secured, these members, however, being insulated from the supporting bracket. The contact member 12^a is electrically connected to one end of the heating element or unit *c* by a strip 35. The opposite end of the heating unit is directly connected to a terminal post by a strip 37, and the contact member 12 is connected by a strip 38 to the other terminal post 36. It will thus be seen that the current will normally flow through one of the terminal posts, strip 37, the electrical heating unit *c*, the strip 35, contact 12^a, circuit closing element 11, contact 12, strip 38, and the other terminal post 36 connected with the last mentioned strip.
- 25 40 45 50 55 60 65 For the purpose of re-setting or re-latching the circuit breaker, there is provided on the top of the cover *e* and beneath the strap or bail *h'* of the handle a setting lever 13 connected to the cover *e* by means of a pin 41 fixed to the cover and engaging in an elongated slot 42 in the lever. The lever 13 has an upwardly extending projection or lip 43 by means of which the lever may be thrown, and this projection or lip normally lies close to the side of the handle strap *h'*, where it is out of the way. It will be seen, particularly from Fig. 2, that the casing is provided with beads 44 upon which the handle bail rests, and there is thus provided between the handle bail and the casing a

space for the lever 13. Carried by the latch plate 10 and extending through an arcuate elongated opening 45 in the casing *e* is a pin or stud 46 to the upper end of which the lever 13 is pivotally connected. The lever 13 has a thickened boss 47 for receiving this pin, and the strap *h'* is offset upwardly as at 48 to accommodate this boss.

The operation of the device is briefly as follows. Assuming that the parts of the circuit breaker are in latched or "on" position, as shown in Fig. 1, so that the current is flowing through the heating unit; when the temperature of the utensil gradually rises, the bi-metal bars 14 and 15 are flexed or bowed in opposite directions. Since the shoulder 30 of the latch plate is urged against the anti-friction roller 19 carried by the bar 14, this bar bends at its intermediate portion towards the center of the iron, causing the plate 16, to which the parts are secured, to turn slightly in a clockwise direction. Owing to this turning movement of the plate 16 and the flexure of the bar 15, the free end of the latter, when the predetermined temperature is reached, at which the device is set to operate, engages the adjustable stop 21 whereupon the anti-friction roller 19 will be disengaged from the latch plate permitting the latter, under the influence of the spring 24, to rotate in a direction to withdraw the circuit closing element 11 out of engagement with the contacts 12 and 12^a, thereby breaking the circuit through the heating unit. The parts will now assume the position shown in Fig. 3. It will be observed that the two thermostatic bars, when heated, are flexed in opposite directions and the arrangement is such that the flexure or movement of both of these bars is combined or aggregated to release the circuit breaker. The thermostatic bars are placed side by side so that they take but a relatively small amount of space. Thus, there is provided an arrangement which, while extremely compact, has a thermostatic device of sufficient capacity and size to operate positively and sensitively at any desired predetermined temperature at which the device may be set to throw the current "off". Owing to the provision of the anti-friction roller 19, friction between the thermostat and the latch plate is reduced to a minimum. The roller will readily ride out of engagement with the latch plate when the thermostat has been flexed to a predetermined extent, and sticking of the parts is practically eliminated.

One of the advantages of the arrangement illustrated and described is that the circuit breaker may be re-set into circuit closing position a very short time after the breaker is operated to break the circuit; that is to say, the operator of the iron need allow but a very little time for the iron to cool slightly

before he can again throw the current onto the heating unit, this being due to the fact that the thermostatic bars simultaneously flex back towards each other upon being cooled, thus permitting the roller 19 to be brought into engagement with the latch plate more quickly than would otherwise be the case. To re-set the device, it is merely necessary for the operator to place his finger 10 against the lip 43 of the lever 13 and move this lever beneath the bail of the handle, and when the lever is in final position, the lip 43 lies closely to the bail so that it is out of the way and causes no annoyance or inconvenience. It will be understood that when the lever is thus pushed to re-set the device, the lever is fulcrumed against the pin 41 and moves, through the pin 46, the latch plate to the position shown in Fig. 1. All of the 20 parts of the circuit breaker are enclosed within the casing and are thus protected and do not in any way mar the appearance of the iron. The lever 13 is so positioned that it is practically out of sight.

25 I claim as my invention:

1. A thermal circuit breaker including a circuit closer, and thermostatic means normally holding said closer in circuit closing position, said means including a plurality of 30 thermostats, one of which is arranged to normally hold said closer in circuit closing position and the other of which is arranged to move said first thermostat, said thermostats being so arranged that their responses to 35 temperature changes are combined to effect release of the closer.

2. A thermal circuit breaker including a circuit closer, a pivoted member, a thermostatic member carried by said pivoted member and normally holding said closer in circuit closing position, and a second thermostatic member arranged to move said pivoted member and thermostatic member carried thereby.

45 3. A thermal circuit breaker including a circuit closer, a pivoted member, and thermostatic means normally holding said circuit closer in circuit closing position, said means comprising a plurality of thermostatic elements carried by said pivoted member and so arranged that their responses to temperature changes are combined to effect release of said closer.

4. A thermal circuit breaker including a 55 circuit closer, thermostatic means normally holding said closer in circuit closing position, said means comprising a plurality of thermostatic elements movable in opposite directions upon temperature changes and so arranged that their responses to temperature changes are combined to effect release of said closer, and adjustable means for regulating the operation of said thermostatic means.

65 5. A thermal circuit breaker including a

circuit closer, means normally urging the same into open position, a plurality of thermostatic elements normally holding said closer in circuit closing position, one of said elements being engaged with said closer and the other of said elements being associated with the first one and arranged to disengage the same from said closer, and adjustable means constituting a stop against which said second mentioned element is adapted to 75 engage.

6. A thermal circuit breaker including a circuit closer, means normally urging the same into open position, a pivoted member, and a pair of thermostatic bars carried by 80 said pivoted member and arranged to normally hold said closer in circuit closing position.

7. A thermal circuit breaker including a circuit closer, an abutment, and a pair of 85 thermostatic bars placed side by side and adapted to flex in opposite directions, one of said bars being engageable with said circuit closer to hold the same in circuit closing position, and the other of said bars being 90 operatively connected to and movable with said first bar and adapted to engage said abutment and thereupon move said first bar.

8. A thermal circuit breaker including a circuit closer, an adjustable abutment, and a pair of thermostatic bars placed side by side and adapted to flex in opposite directions, one of said bars being engageable with 95 said circuit closer to hold the same in circuit closing position, and the other of said bars being operatively connected to and movable with said first bar and adapted to engage said abutment and thereupon move said first bar.

9. A thermal circuit breaker including a 105 circuit closer, an abutment, and a pair of thermostatic bars connected together and pivotally mounted, one of said bars being engageable with said circuit closer and, when flexed under heat changes, adapted to 110 move the other or second of said bars towards said abutment, and said second bar being adapted to engage said abutment and thereby move said first bar out of engagement with said closer.

10. A thermal circuit breaker including a 115 pair of contacts, a circuit closer having a latch plate pivoted at one side and a circuit closing element resiliently connected to said plate and adapted to engage said contacts, a spring associated with said plate for normally urging the same in a direction to withdraw said element from said contacts, said plate having, at the side opposite the pivotal point, a shoulder, a thermostatic bar 120 flexible in the plane of said plate and adapted to engage said shoulder, and means for moving said circuit closer into circuit closing position.

11. A thermal circuit breaker for elec- 130

- trically heated utensils, including a supporting plate, a cover housing said supporting plate, a pair of contacts, a circuit closer having a latch plate pivoted to said supporting plate and located beneath said cover, said closer further including a circuit closing element carried by said latch plate, thermostatic means carried by said supporting plate and arranged to hold said closer in circuit closing position, and pivoted means for re-setting said latch plate in circuit closing position connected to said latch plate and extending through an arcuate slot in said cover.
12. A thermal circuit breaker for electrically heated utensils, including a supporting plate, a cover housing said plate, a pair of contacts, a circuit closer having a latch plate pivoted to said supporting plate and located beneath said cover, said closer further including a circuit closing element carried by said latch plate, thermostatic means carried by said supporting plate and arranged to hold said closer in circuit closing position, a lever resting on the outside of said cover, a stud pivotally connecting said lever to said latch plate, and a pin connecting said lever to said cover, said cover hav-
- ing an arcuate slot to accommodate said stud and said lever having a slot to accommodate said pin.
13. A thermal circuit breaker for electrically heated utensils, including a supporting plate, a cover therefor, a strap connected to said cover, a circuit closer beneath said cover, thermostatic means for normally holding said closer in circuit closing position, and a lever positioned between said strap and cover and operatively connected to said circuit closer for re-setting the latter in circuit closing position.
14. A thermal circuit breaker for electrically heated utensils, including a cover, a strap connected to said cover, a circuit closer having a pivoted plate mounted beneath said cover, thermostatic means beneath said cover for normally holding said closer in circuit closing position, and a lever comprising a plate positioned between said strap and cover and operatively connected to said closer for moving the same into circuit closing position, said lever having an upstanding lip adapted to lie closely against said strap when the lever is in its normal position.

JOSEPH F. SMART.
